US00D771087S

(12) United States Design Patent (10) Patent No.: US D771,087 S
Lee et al. (45) Date of Patent:  Nov. 8, 2016

(54) DISPLAY OF A TELEVISION RECEIVER WITH GRAPHICAL USER INTERFACE

(71) Applicant: LG ELECTRONICS INC., Seoul (KR)

(72) Inventors: Kun Sik Lee, Seoul (KR); Gang Seub Lee, Seoul (KR); Uni Young Kim, Seoul (KR)

(73) Assignee: LG ELECTRONICS INC., Seoul (KR)

() Term: 14 Years

(21) Appl. No.: 29/490,587

(22) Filed: May 12, 2014

(30) Foreign Application Priority Data

Dec. 5, 2013 (KR) 30-2013-0061475

(51) LOC (10) Cl. 14-04

(52) U.S. Cl.

USPC D14/486

(57) CLAIM

We claim the ornamental design for a display of a television receiver with graphical user interface, as shown and described.

DESCRIPTION

The sole FIGURE is a front view of a display of a television receiver with graphical user interface showing the new design.

The broken line showing of the display screen forms no part of the claimed design. The broken line showing of the remainder of the user interface is for environmental purposes only and forms no part of the claimed design.

1 Claim, 1 Drawing Sheet
